UNITED STATES PATENT OFFICE.

LOUIS GRIMOND MACINTYRE, OF BROUGHTY FERRY, SCOTLAND.

CONNECTION WITH BALLING MACHINES FOR SLIVER AND THE LIKE.

1,404,623.

Specification of Letters Patent. Patented Jan. 24, 1922.

Application filed November 5, 1920. Serial No. 421,909.

To all whom it may concern:

Be it known that I, LOUIS GRIMOND MACINTYRE, a subject of the King of Great Britain and Ireland, and a resident of Carbet Castle, Broughty Ferry, in the county of Forfar, Scotland, manufacturer, have invented certain new and useful Improvements in Connection with Balling Machines for Sliver and the like, of which the following

10 is the specification.

The invention relates to balling machines of the type shown in my British Patent 23,037/13 and in which a ball, or more correctly a cheese or short cylinder of sliver 15 or the like, is formed between discs upon a withdrawable centre by the action of drums engaging its periphery.

In operating this type of machine, considerable difficulty is experienced at the commencement of the ball, as owing to the soft and filamentous form of the sliver, it is not immediately picked up by the centre, and the centre (owing to some extent to the inertia of its mass) does not instantly commence rotating with the peripheral speed of the balling drums. Thus, the sliver is apt to become folded or looped upon the centre, so causing the formation of an irregular ball.

The invention has for its object to provide means for ensuring that at the commencement of a ball the centre shall rotate at its true peripheral speed, and thus ensure that the early convolutions of the sliver shall lie upon it smoothly and evenly.

35 According to the invention, means are provided for driving the centres at the commencement of the ball, otherwise than by mere contact with the surface of the balling drums, either directly, or through the first 40 few turns of sliver. These means are such that they automatically pass out of engagement as the ball increases in size. For example, the means may consist of teeth cut upon the periphery of one of the balling

45 drums which engage teeth cut upon the periphery of the centre, which teeth may extend wholly, or only partially across the drum and centre. Or the balling centre may be constrained to rotate upon the spindle 50 upon which it is carried, and that spindle be driven by toothed or other gearing at the proper relative speed from the spindle of the balling drum, the driving means being so arranged that upon the centre spindle 55 moving radially away from the balling drum spindle as the ball increases in size, the driv-

ing means moves out of engagement. Thus the balling centre is driven positively at its correct speed until the ball has reached such a size that slip and folding of the sliver cannot take place, thereafter, the driving means passing out of engagement, the ball continues to be built by its surface contact with the balling drum in usual manner.

Three illustrative examples of the carrying out of the invention are shown on three accompanying sheets of explanatory drawings, Figures 1 and 2, Sheets 1 and 2 being respectively a part-sectional front elevation and a side view in diagram of a withdrawable balling centre to which the invention has been applied. Figure 3, Sheet 2, shows the same application to another type of centre, Figures 4 and 5, Sheet 3, are illustrative of an alternative method of securing an initial positive drive to the balling centre, while Figures 6 and 7 are a sectional elevation and a plan of certain details drawn to an enlarged scale.

In the first example the balling centre 80 consists of two coaxial cylindrical members A carried on endwise movable spindles B and journaled within hollow trunnion bearings C. The trunnions are supported by blocks D interconnected by a stirrup E and 85 located in vertical guides in the framing of the machine. These guides are not shown in the drawings but their positions are indicated by dotted lines D¹ in Figure 1. So mounted upon the centre parts A, as to 90 rotate with the latter, are two parallel discs F between which the ball of sliver is formed. Coacting clutch devices G are provided on the abutting faces of the members A, which are adapted in a manner hereinafter described to be withdrawn into the hollow trunnions C when the formed ball is to be freed from engagement.

The balling centre is located between two forming drums H, J, the former of which is 100 plain and the latter provided with teeth J¹ adapted to engage teeth A¹ of the same pitch on the peripheries of the centre parts A. The drums H, J, are rotated in the same direction at the same speed and at the commencement of the balling operation, that is, just prior to the sliver being presented to the centre, the teeth on the latter are fully engaged by the teeth J¹, and thus both drums and centre rotate with the same peripheral 110 speed, the teeth A¹ on the centre just clearing the plain surface of the drum H. Under

these conditions sliver is delivered to the centre and is immediately engaged in the nip between the latter and one of the forming drums. As the layer wound on to the 5 centre increases in thickness, the teeth A¹ are gradually moved out of engagement with the teeth J¹ on the drum, and thereafter the drive is continued in usual manner by frictional contact between the sliver on the 10 centre and the two drum surfaces.

On the spindles B carrying the centre parts are keyed cylindrical slippers K in a groove in the periphery of which there are cod pieces K' carrying pins as shown in detail in 15 Figures 6 and 7 engaging in slides M supported on the machine framing and terminating in outwardly curved arms M¹. As winding proceeds the sliver itself raises the centre and with it the blocks D which move 20 vertically upwards in their guides. After a predetermined amount of sliver has been wound on, the blocks D and centre A are raised still further by means of a chain O engaging the stirrup E and operated through 25 suitable mechanism (not shown) from the machine drive. At this stage the slipper pins L, which have up till now been travelling in the lower parallel portions of the slides M, encounter the curved arms M¹ and in riding up the latter force the spindles B outwards and free the centre parts A from engagement with the wound ball which may 30 then be discharged from between the discs F.

The second example shows the same 35 method of securing a positive drive at the outset as applied to a balling machine in which the centre is made in one piece withdrawable within a single trunnion from one side of the machine. The construction of the 40 centre will be clearly understood from Figure 3. In this case the centre R is carried on a spindle S, a slipper K which operates through a slide M as hereinbefore described to withdraw the centre within a single trunnion bearing T, when the formed ball is to 45 be freed. The return movement of the parts to their starting position is assisted by springs L' in compression on bolts N secured at one end to a disc N' fixed on the spindle 50 S and extending at their outer ends through lugs P' on the blocks D. The drive for the balling centre is the same as before, two forming drums H, J, being provided, with the latter in toothed engagement with the 55 centre and supplying the initial positive drive thereto.

In some circumstances, as for example 60 when a delicate fibre liable to be damaged by engagement with the teeth on the centre and forming drum, is being treated in a balling machine, it is desirable that the positive drive should be arranged external to the actual balling centre and forming drums. Such an arrangement is shown in Figures 65 4 and 5, Sheet 3, as applied to a machine of

the type described in the first example. In this case the peripheries of the centre parts A are smooth and so also are those of the drums H, J. Outside the centre carriage is a spur wheel P carried on one of the drum 70 shafts and engaging a pinion Q mounted on one of the centre-carrying spindles B. The wheels P, Q, are so proportioned that when in gear the centre is driven at the same surface speed as the forming drums. In this 75 way a positive drive to the centre is ensured at the outset of the balling operation, and as the centre with its carriage is raised by the action of the sliver as it is wound, the teeth on the wheels P, Q, are gradually disengaged and the drive finally continues as 80 before by frictional contact between the surface layer on the centre and the peripheries of the forming drums. One or both of the latter may be leather sheathed to enhance 85 the contact grip. It is obvious that this form of drive is equally applicable to a machine of the type shown in Figure 3 of the drawings.

What I claim is:—

1. In balling machines of the type referred to for the treatment of sliver and the like, means for driving the balling centre positively at the commencement of the ball, which means pass automatically out of engagement as the ball increases in size, as and for the purposes set forth.

2. In the mechanism forming the subject-matter of claim 1 hereof, teeth upon the periphery of the balling centre adapted to 100 be engaged directly or through the first few turns of sliver by teeth of the same pitch upon the periphery of one of the usual forming drums, as set forth.

3. In the mechanism forming the subject-matter of claim 1 hereof, positive driving means between the balling centre and one forming drum located external to the actual centre and drum surfaces which are smooth, as set forth.

4. In the mechanism forming the subject-matter of claim 1, a forming drum shaft, a spur wheel driven from said shaft, a spindle for the balling center, a pinion mounted upon said spindle and engaging said spur 115 wheel, the proportions of the spur wheel and pinion being such that when the latter are in gear the centre rotates with the same peripheral speed as the forming drum, as set forth.

5. In the mechanism forming the subject-matter of claim 1, a vertically guided carriage housing the balling centre and movable bodily upwards by the direct action of the sliver as it is wound upon the centre, as and for the purposes set forth.

In testimony whereof I have signed my name to this specification.

LOUIS GRIMOND MACINTYRE.
